UNITED STATES PATENT OFFICE.

ERNST II. HUENEFELD, OF CINCINNATI, OHIO.

DESIGN FOR A BAKE-OVEN.

SPECIFICATION forming part of Design No. 25,782, dated July 14, 1896.

Application filed May 23, 1896. Serial No. 592,885. Term of patent 14 years.

To all whom it may concern:

Be it known that I, ERNST II. HUENEFELD, a citizen of the United States, residing at Cincinnati, in the county of Hamilton and State 5 of Ohio, have invented and produced a new and original Design for Bake-Ovens, of which the following is a specification, reference being had to the accompanying drawings, forming a part thereof.

10 Figures 1 and 2 are views in perspective, which I deem necessary to fully disclose my design.

The leading feature of my design consists in a raised surface on the door of the oven, 15 quadrangular in shape, as shown in Fig. 1, or rectangular, as shown in Fig. 2, provided centrally with a raised figured surface surrounded by a circular rib. Located centrally within the figured surface is a rectangular 20 name-plate, and below the quadrangular or rectangular door is a flat ring.

A represents the quadrangular or rectangular shaped door, having a raised portion B, the edges of the raised portion being approximately parallel with the edges of the door. 25 Located centrally is the figured surface C, surrounded by the circular rib D, and between the rib and raised figure C are a series of semi-cylindrical projections, and centrally within the figured section C is the rectangular name- 30 plate D.

Located below the oven-door is the flat ring, having projecting portions at diametrically opposite points and forming a frame for a window. 35

What I claim is—

The design for a bake-oven herein shown and described.

ERNST II. HUENEFELD.
